UNITED STATES PATENT OFFICE.

EUGENE CHIPPEAUX, OF ARCADIA, KANSAS.

WIRE GUIDE AND TUBE CLEANER.

Application filed February 21, 1924. Serial No. 694,446.

To all whom it may concern:

Be it known that EUGENE CHIPPEAUX, a citizen of the United States, residing at Arcadia, in the county of Crawford and State 5 of Kansas, has invented certain new and useful Improvements in Wire Guides and Tube Cleaners, of which the following is a specification.

This invention relates to wire guides and 10 tube cleaners and it consists in the novel features hereinafter described and claimed.

An object of the invention is to provide a device of the character stated especially adapted to be used by miners for cleaning 15 their lamp tubes, whereby the cleaning operation may be accomplished in the dark.

Owing to the fact that miners are confined for long periods of time in darkened cavities, they as a general rule have poor eyesight and are unable to promptly direct 20 cleaning devices to the openings in their lamps to clean them. It is an object of the present invention to provide means for readily directing the cleaning member of the device toward the opening in the lamp so that 25 the device may be passed through the opening by simply pushing the same and not by twisting and during the longitudinal movement of the cleaning element, the obstruction which is in the lamp is removed and 30 the opening therein is cleaned.

The device includes a cylinder provided at one end with a socket having a cone-shaped wall and a cone-shaped nipple portion 35 centrally positioned in the socket. A hole passes longitudinally through the inner end wall of the said socket and is extended into a sleeve provided at the interior of the cylinder. The opposite end portion of the cylinder is closed by a screw cap. A stem 40 is mounted for longitudinal movement in the cylinder and through the cap thereof and is provided with a reduced end portion which operates through the wall adjacent the socket. A coil spring is housed within 45 the cylinder and interposed between the end wall thereof and a disk mounted upon the said stem. The spring is under tension with a tendency to hold the reduced end of the stem housed in the sleeve and the nipple of 50 the cylinder. Tubular casing sections are applied to the opposite ends of the cylinder and they house the inlet opening of the socket and also the outer end of the stem and 55 the head which is mounted thereon.

In the accompanying drawing:

Figure 1 is a longitudinal sectional view of the wire guide and tube cleaner.

Figure 2 is a transverse sectional view thereof, cut on the line 2—2 of Figure 1. 60

Figure 3 is a side elevation of the same.

The wire guide and tube cleaner comprises a cylinder 1 provided at one end with a socket 2 having conical side walls 3 which merge at their inner portions in arcuate surfaces 4 and the said surfaces are extended into the side surfaces of a cone-shaped nipple 5 located at the center of the socket 2. A solid wall portion 6 is disposed transversely across the interior of the cylinder 1 behind the socket 2 and a sleeve 7 extends inwardly from the wall 6 and is concentrically positioned with relation to the cylinder 1. A bore 8 traverses the length of the sleeve 7, passes transversely through the wall 6, and traverses the length of the nipple 5 and opens at the pointed end thereof. A cap 9 is screwed into the opposite end of the cylinder 1 and is provided with a central opening 10. A stem 11 is slidably mounted in the cylinder 1. The intermediate portion of the stem 11 passes through the opening 10 and the end portion of the said stem enters the bore 8. That portion of the stem 11 which enters the bore 8 is 75 reduced diametrically and forms a wire shaped extremity 12 which is pointed at its end as at 13.

A disk 14 is mounted upon the intermediate portion of the stem 11 and is housed 80 within the cylinder 1. A coil spring 15 is interposed between the inner surface of the wall 6 and the inner surface of the disk 14 and is under tension with a tendency to hold the disk 14 toward the inner surface 95 of the cap 9. A head or button 16 is mounted upon the outer end of the stem 11. Cylindrical casing members 17 and 18 are arranged to slide over the exterior surface of the cylinder 1 and enclose the end portions thereof and the inner edges of the said casing sections 17 and 18 are adapted to abut against an annular flange 19 provided at the intermediate portion of the exterior surface of the cylinder 1. 100

In operation, the casing sections 17 and 18 are removed from the cylinder 1 and the end of the tube which is to be cleaned is inserted in the socket 2 whereby the conical walls 3 center the said tube and direct the same in 110

alinement with the reduced end portion 12 of the stem 11. The stem 11 is then moved inwardly against the tension of the spring 15 by pressing upon the head 16 and the 5 reduced end portion 12 of the said stem is forced into the tube and a passageway through the tube is opened.

Therefore it will be seen that the tube may be cleaned by inserting the end thereof 10 in the socket and this may be accomplished in the dark, as well as in the light and when the end of the tube is inserted in the socket the opening or passageway through the tube is positioned in alinement with the stem 15 so that when the stem is moved the cleaning end thereof is passed through the tube and the passageway through the tube is readily 15 opened or cleaned.

Having described the invention, what is 20 claimed is:

A wire guide and tube cleaner comprising

ing a cylinder provided at one end with a socket having a conical surface which merges at its inner portion with arcuate surfaces, said arcuate surfaces merging with 25 the exterior surfaces of a cone-shaped nipple provided at the center of the socket, a wall disposed transversely of the cylinder at the inner end of the socket and provided at its inner face with a sleeve, the bore of 30 the sleeve passing transversely through the wall and traversing the length of the nipple, a cap closing the opposite end of the cylinder, a spring interposed between the wall and a member fixed to the stem, said 35 stem having a diametrically reduced end portion which is normally housed within the bore, and a disk carried at the outer end of the stem.

In testimony whereof I affix my signature.

EUGENE CHIPPEAUX.
